Primary Examiner — George D Kirschbaum*Assistant Examiner* — Amy Wierenga(74) *Attorney, Agent, or Firm* — Banner & Witcoff, Ltd.(57) **CLAIM**

The ornamental design for a fitting for a faucet, as shown and described.

DESCRIPTION

FIG. 1 is a top perspective view of a fitting for a faucet showing our new design;

FIG. 2 is a bottom perspective view thereof;

FIG. 3 is a top plan view thereof;

FIG. 4 is a bottom plan view;

FIG. 5 is a front view thereof;

FIG. 6 is a rear view thereof;

FIG. 7 is a left side elevational view thereof; and,

FIG. 8 is a right side elevational view thereof.
